UNITED STATES PATENT OFFICE.

ELDRIDGE JUDSON GODARD, OF ANAGANCE, NEW BRUNSWICK, CANADA.

SNOW-PLOW.

SPECIFICATION forming part of Letters Patent No. 415,103, dated November 12, 1889.

Application filed April 27, 1889. Serial No. 308,826. (No model.)

To all whom it may concern.

Be it known that I, ELDRIDGE JUDSON GODARD, a citizen of the United States, residing at Anagance, in the county of Kings, New Brunswick, Canada, have invented a new and useful Snow-Plow, of which the following is a specification.

My invention relates to improvements in snow-plows; and it consists in certain novel features hereinafter described and claimed.

In the accompanying drawings, Figure 1 is a perspective view. Fig. 2 is a plan view. Fig. 3 is a central vertical longitudinal section. Fig. 4 is a transverse vertical section looking toward the front. Fig. 5 is a detail perspective view of the rotary knives. Fig. 6 is an enlarged side view of the wheel-scrapers and the levers for operating the same.

In carrying out my invention I employ the longitudinal beams A A, in which the axles B B, carrying the supporting-wheels C C, are journaled, and these beams are connected at their front and rear ends by the cross-bars D D, as shown. Upon the upper side of the rear cross-bar D, I secure a transverse end plate E, in which the coupling F is mounted, so that the plow can be coupled to the front of a locomotive to be pushed through the snow.

To the front ends of the beams A A, I secure the forwardly-projecting scraper G, the upper surface of which is inclined upward and rearward, and is divided into a series of longitudinal troughs H, separated by vertical tongues I, having sharpened front ends, so that the snow will be thoroughly cut up and broken as the machine is pushed forward. The floor J extends rearward from the scraper G on an upward incline, so that as the machine is pushed forward a wedging action will be exerted on the bank of snow from the bottom of the same, so as to lift it and divide it, as will be readily understood. Beneath the floor J, at the side edges of the same, I secure the depending vertical plates K, which extend outside the wheels, so as to protect them from the snow and prevent the snow working under the machine, so as to throw it from the track.

On the upper side of the floor J, I arrange the deflecting-plates L L, which have their

front ends arranged close together in the central longitudinal line of the machine and diverge rearwardly therefrom, their rear ends being secured to the sides of the machine. These deflecting-plates serve to direct the snow to one side as it is broken up by the machine and moves up the inclined floor of the same. On the sides of the machine, adjacent to the ends of these deflecting-plates, I arrange the wings M, which are pivotally secured to the frame, and are operated so as to be turned inward or outward by a double crank N on a vertical rock-shaft O, mounted in the floor near the rear end of the same and provided with a hand-wheel P at its upper end, so that it may be operated through suitable chains from the locomotive, the wings being connected to the said double crank by the pitmen N'.

On the upper side of the floor J, at the side edges of the same and near the front end thereof, I erect the walls Q, which are secured to suitable supporting-standards R and braced by the cross-beams S, as shown. Between the front ends of these walls Q, I secure a series of rigid horizontal knives T, which are adapted to enter the snow-bank and cut and break up the snow, and these knives are braced by a standard U, erected on the scraper at the center of the same, as clearly shown. In rear of these stationary knives T, and adjacent to the front ends of the deflecting-plates L, I mount a rock-shaft V, having a hand-wheel W at its upper end, to which suitable chains are secured and extended back to the locomotive. On this rock-shaft V, I secure the forwardly-projecting vertical cut-off plate X, which is adapted to be turned to one side or the other to throw the snow to one or the other side, as will be readily understood. If the machine is being used on a single track this plate X can be left in the central line thereof, so that the snow will be thrown to both sides and the strain on the machine thereby distributed and lessened. Between this plate and the side walls Q, I arrange a series of vertical stationary knives Y, adapted to act on the snow as it passes up the floor J, so as to break up the same. In rear of these stationary vertical knives Y, I arrange a horizontal rotary shaft Z, which is journaled in the walls Q and the deflecting-plates L, and is provided

at its center with a grooved pulley or disk *a*, connected by a belt *b* with a similar pulley *c* on the rear axle, as shown. This shaft *Z* is provided with a number of radial knives *d*, 5 and as the machine is pushed forward will be rotated through the belts and pulleys described, so that the said radial knives will be forced to thoroughly agitate the snow and break it up into small particles.

10 To the inner sides of the beams *A A*, I pivot the levers *e*, which are connected at their rear ends by the cross-bars *f*, and have the scrapers *g* depending from their front ends and adapted to act on the front wheels.

15 In rear of these levers *e*, I pivot to the beams *A* the similar levers *h*, which have the scrapers *i* depending from their rear ends and adapted to act on the rear wheels, and the front ends of the levers *h* are pivoted to 20 the levers *e* between the pivot of the same and the rear end thereof, so as to secure a simultaneous operation thereof. These levers are operated by means of a vertically-reciprocating bar *j*, connected at its lower end to the 25 cross-bar *f* and extending upward through the rear end of the machine, and a hand-lever *k*, pivoted at one end upon the frame and at an intermediate point to the upper end of the bar *j*.

30 From the foregoing description, taken in connection with the accompanying drawings, it is thought that the operation of my improved snow-plow will be readily understood. The plow is coupled in front of a locomotive 35 and is pushed forward thereby into the snow-bank, so as to break up the snow and throw it to the side of the track, leaving the track free for the passage of the train. The scraper *G* at the front end of the machine has its front 40 edge about on a level with the top edges of the rails, so that the said scraper will enter the snow-bank near the ground and consequently lift the same, so as to loosen and separate the particles of snow. As the machine 45 is pushed forward the stationary horizontal knives, the stationary vertical knives, and the rotary knives act successively on the snow, so as to thoroughly break up and separate the particles thereof. At the same time the 50 snow will be forced up the inclined floor of the machine and thrown to one side by the deflecting-plate, as will be readily understood, and in order that the snow may not fall back in rear of the plow the wings *M* are thrown 55 out, so as to push the snow away from the sides of the plow.

It will be seen from the foregoing that I have provided a very strong and durable

snow-plow by the use of which large snow-drifts can be readily broken up and removed 60 from the track without great strain being thrown on the locomotive, and its advantages are thought to be obvious. The axle may be provided with a loose drum, so that when there is no necessity for the rotary knives 65 operating, the belt can be shifted onto this loose drum, as will be readily understood.

Having thus described my invention, what I claim, and desire to secure by Letters Patent, is—

1. In a snow-plow, the combination of the scraper provided in its upper side, at its front end, with a series of inclined longitudinal troughs *H*, separated by the vertical partitions *I*, having sharpened front ends, the vertical walls *Q* at the side edges of the scraper, and the horizontal stationary knives secured to the side walls *Q* and extending between the same above and out of contact with the partitions *I*, as set forth. 75

2. In a snow-plow, the combination, with the frame, of the wings pivotally mounted on the sides of the same, the vertical rock-shaft arranged between the wings, the double crank on said shaft, and the pitmen connecting said 85 crank with the wings, as set forth.

3. A snow-plow having the horizontal stationary knives *T* at its front end and having stationary vertical knives *Y* arranged in rear of the said horizontal knives, as set forth. 90

4. A snow-plow having the horizontal knives *T*, the vertical knives *Y* in rear of the horizontal knives, and rotary knives arranged in rear of the vertical knives, as set forth.

5. The combination, with the beams *A*, of 95 the levers pivoted thereon and having scrapers at their ends adapted to act on the wheels, as set forth.

6. The combination, with the beams *A*, of the levers *e*, pivoted thereon, the scrapers depending from said levers and adapted to act on the front wheels, the levers *h*, pivoted thereto and also to the levers *e*, the scrapers depending from said levers and adapted to act on the rear wheels, the cross-bar *f*, connecting the ends of the lever *e*, the bar *j*, connected to the cross-bar *f*, and the hand-lever *k*, adapted to depress said bar, as set forth. 105

In testimony that I claim the foregoing as my own I have hereto affixed my signature in 110 presence of two witnesses.

ELDRIDGE JUDSON GODARD.
